CLAIM

The ornamental design for a paper clip, as shown and
described.

DESCRIPTION

FIG. 1 is a front elevational view of a paper clip showing
my new design;

FIG. 2 is an side elevational view, all other sides being
identical;

FIG. 3 is a front elevational view of a second embodiment
of my new design, the rear view being a mirror
image thereof; and,

FIG. 4 is a rear elevational view of FIG. 1 drawn to a
reduced scale.

The fragmentary sheets of paper depicted by means of
broken lines in FIG. 1 are shown for illustrative pur-
poses only and form no part of the claimed design.
